His Attorney.

UNITED STATES PATENT OFFICE

2,170,694

ELECTROMAGNETIC SWITCH AND SYSTEM
THEREFORCharles L. Perry, Schenectady, N. Y., assignor to
General Electric Company, a corporation of
New York

Application October 1, 1937, Serial No. 166,787

7 Claims. (Cl. 175—294)

My invention relates to electromagnetically operated switches and has for its object a simple and reliable electromagnetic switch and system therefor which is held closed by a magnet made of permanently magnetizable material, and which may be opened and closed by operating coils or opened on overload by a current responsive coil.

In one form of my invention I provide an electromagnet for closing the switch, this magnet being provided with an armature connected to the switch and a magnet frame member provided with a portion hereinafter called the holding magnet, made of a material having a high coercive force which holds residual flux when magnetized so as to hold the switch closed. An operating coil is provided for attracting the armature to close the switch. A second operating coil connected to oppose the holding magnet is provided for releasing the armature to allow the switch to open, and if desired, one or more additional coils also opposing or neutralizing the holding magnet may be provided and energized in response to the current in the switch so as to open the switch on overload.

For a more complete understanding of my invention, reference should be had to the accompanying drawing, Fig. 1 of which is a side elevation view of a switch embodying my invention; while Fig. 2 is a diagram of a control system for an electric motor utilizing this switch.

Referring to the drawing, in carrying out my invention, I provide a pivoted armature 10 mounted rigidly on a pivot shaft 11 together with a magnet frame member 12 of soft magnet core iron and a plurality of operating coils 13, 14, 15 and 16 provided with an axially extending core 17. This core 17 which forms a field structure with the member 12 has a relatively short circular or disk-shaped portion 18, forming a holding magnet, made of a suitable material having a high coercive force, and a relatively long portion made of soft magnet core iron constructed in two parts, 19 and 20. Although the two parts, 19 and 20, could be made as one, the provision of the relatively short section 20 makes it possible to leave out this section in the event that the portion 19 is long enough to form, with the portion 18 a core of the desired length. The armature 10 is provided with a member 20a made of magnet core iron extending across the ends of the core 17 and the frame member 21 when the armature is in attracted position as shown in Fig. 1 to complete a magnetic flux path between them.

The portion 18 is preferably made of a material of high magnetic coercive force consisting

mainly of aluminum, nickel and iron, such as described and claimed in Patent No. 1,968,569, issued July 31, 1934, to William E. Ruder. Preferably I use an alloy consisting of 12% aluminum, 20% nickel, and 5% cobalt, the balance being iron.

As shown, the core portion 18 forming the holding magnet has a length in the direction of the lines of magnetic force, i. e. axially of the coils 13 to 16, which is only a fraction of its diameter 10 as shown in Fig. 1. I have found that this construction provides for much greater magnetic pull on the armature per unit weight of holding magnet material than a construction of smaller diameter and greater axial length. For example, a core of this material, four and one-quarter inches (4 1/4") long by two inches (2") in diameter, in one device gave less pull on the armature than a core one inch (1") long with a diameter of two and one-quarter inches (2 1/4"), the remainder of the core in each case being of soft steel. Another advantage of the axially short holding magnet is that fewer turns in the operating coil are required to pick up the armature.

It will be understood that the movably mounted contacts of the switch are mechanically connected to the armature 10. As shown in Fig. 2, the three pivotally mounted contact arms 21 are secured to an extension 22 of the pivot shaft 11 to which the armature 10 is secured. These movable contacts arms, which form with their stationary contacts a three pole switch, are biased to their open circuit positions as by a suitable spring as shown or by the weight of the armature, the armature when released coming to rest against a stop 23 provided for it.

In Fig. 2, I have shown a control system in which the switch of Fig. 1 is embodied, the switch being connected to control the supply of current from suitable three phase mains 24 to a three phase motor 25. In this system the coil 16 serves as an operating coil to pick up the armature and move it to its attracted position.

The coil 15 serves as an opening coil. This coil when energized produces a flux in opposition to the flux of the holding magnet thus neutralizing the magnet and releasing the armature which thereupon drops to move the contact arms 21 to their open circuit positions, as shown in Fig. 2.

The coils 13 and 14 are connected respectively in two of the alternating current supply lines running to the electric motor 25. These coils are energized in response to the current passing through the switch, i. e. the current in the motor 25, and upon the occurrence of a predetermined

current in these coils, neutralize the permanent magnet and allow the armature to drop and open the switch.

I have provided direct current supply mains 26 and 27 for energizing the coils 15 and 16, and also for energizing the coil 28 of a relay provided with bridging switch contacts 29 and 30. This relay is biased to its open position, as shown by gravity, and when the switch arms 21 are in their open circuit positions, as shown, the coil 28 is normally energized. Its circuit leads from main 26 through a normally closed two-way push-button 31, conductor 32, coil 28, and conductor 33 to the main 27.

15 Two interlock switches 34 and 35 are mounted on the frame member 12 with their operating rod 36 in position to be engaged by an extension 10' on the end of the armature 10 when the armature reaches its attracted position. The switch 35 is normally closed whereas the switch 34 is normally opened as indicated in Fig. 2, and the armature when picked up, closes the switch 34 and opens the switch 35, the switches being biased by a spring 37.

25 When it is desired to start the motor, the push-button 31 is pressed to its lowermost position. This first opens the circuit through the uppermost contact of the push-button 31 whereby the circuit for the coil 28 is transferred through the switches 29 and 35. This circuit leads from the main 26 through the conductor 33, the switch 29, conductor 39, switch 35, coil 28, and the conductor 33 to the supply main 27. When a circuit through the lower contact of the push-button 31 is completed, a circuit is established for the coil 16 which picks up the armature 10, closing the switch arms 21. This circuit leads from the supply main 26 through conductor 38, switch 29, conductor 39, the lower pair of contacts of the push-button 31, through the switch 30, conductor 40, and the coil 16 to the supply main 27. When the armature opens the switch 35, the circuit of the coil 28 through this switch is opened whereupon the switches 29 and 30 drop open, thereby opening the circuit for the coil 16. The switch is now closed and the motor 25 energized, the armature 10 being held in its closed position by the holding magnet 18.

Should it now be desired to open the switch arms 21, the push-button 41 is depressed whereby the coil 15 is energized. This circuit leads from the main 26 through the button 41, the switch 34 which is then closed, the conductor 42, and the coil 15 to the main 27.

55 In the event of an excessive load on the motor, the coils 13 and 14 produce jointly a magnetic flux sufficient to neutralize the holding magnet whereupon the armature 10 drops to open the switch arms 21. The coils 13 and 14 are effective to open the switch despite the fact that they are energized with alternating current, for the reason that the alternating flux of these coils neutralizes the residual magnetism of the holding magnet.

60 When the armature is released, the switch 34 opens and switch 35 closes in accordance with their biases and the push-button 31 having been released and its upper pair of contacts being closed, the relay coil 28 is again energized as previously described. The push-button 31 must now be depressed again to energize the coil 16 in order that the switch arms 21 may again be moved to their closed positions. This interlocking arrangement prevents repeated opening and closing 75 of the switch in the event that an overload occurs

at the instant the switch closes and before the push-button 31 is released. Even though the interlock switch 35 is closed when the armature 10 is released, the armature cannot be picked up again because the relay switches 29 and 30 are both open thus maintaining open circuits for the coils 16 and 28. As previously indicated, to reclose the switch the button 31 must be released to close the relay switches 29 and 30, and then pressed.

10 The energization of the coils 13, 14 and 15 to open the switch demagnetizes the holding magnet 18 to a very great extent so that it cannot attract the armature with sufficient force to hold the switch closed. When the pick-up coil 16 is energized, however, the holding magnet is again magnetized and holds the switch closed. A property of this material is that after once being magnetized, it is very readily re-magnetized. The pick-up coil 16 must be energized with direct current in order that the holding magnet may be re-magnetized, while the opening coils 13, 14 and 15 may be energized with either alternating current or direct current. As shown, the coil 15 is energized with direct current and in that case it must be energized in such direction that its magnetic field opposes the field of the holding magnet.

20 It will be noted that the holding magnet 18 is located in a position, axially of the coils, which is remote from the armature 10. In other words, the magnet core iron portions 19 and 20 are next to the armature. This isolation of the holding magnet from the armature assures that the effect of the residual magnetization of the holding 35 magnet will not be sufficiently strong to hold the armature up in case it is accidentally knocked upward, but without completely seating the switch contacts.

25 The electromagnet having a magnetic circuit formed at least in part of permanently magnetizable material disclosed in this application is covered by my copending application, Serial No. 218,829, filed July 12, 1938, for "Electromagnet."

While I have shown a particular embodiment 45 of my invention, it will be understood, of course, that I do not wish to be limited thereto since many modifications may be made, and I therefore contemplate by the appended claims to cover any such modifications as fall within the 50 true spirit and scope of my invention.

What I claim as new and desire to obtain by Letters Patent of the United States is:

1. The combination with a switch provided with a circuit controlling member mounted for movement between two positions and biased to one of said positions, of an operating coil for moving said member to the other of said positions, a magnetic flux core extending axially of said coil having a portion formed of magnetic core iron and another portion formed of a material capable of retaining a high residual magnetic flux for holding said member in said position, and means operated by movement of said member for controlling the circuit of said operating coil.

2. The combination with a switch provided with a circuit controlling member mounted for movement between two positions and biased to one of said positions, of an operating coil for moving said member to the other of said positions, a magnetic flux core extending axially of said coil having a portion formed of magnet core iron and another portion formed of a material having a high coercive force consisting mainly 75

of nickel, aluminum and iron, and switching means operated by said member for controlling the circuit of said operating coil when said member moves to said other position.

5 3. The combination with a switch provided with a movably mounted contact biased to its open circuit position, an armature connected to said movable contact, a field structure provided with a portion made of permanently magnetizable material having a high coercive force forming a magnet for holding said armature in a closed circuit position, said portion being remote from said armature, an operating coil on said field structure for moving said armature to the closed circuit position, electrical connections for controlling the energization of said operating coil including a switch connected with the circuit of said operating coil so as to deenergize said coil when said switch is opened, and a mechanical connection between said switch and said armature for opening said switch when said armature is moved to its closed circuit position by said operating coil.

15 4. The combination with a switch provided with a movably mounted contact biased to its open circuit position, an armature connected to operate said movable contact to its closed circuit position, a field structure provided with a portion of permanently magnetizable material forming a magnet for holding said armature in said closed circuit position, an operating coil on said field structure for moving said armature to said closed circuit position, a switch operated by said armature to deenergize said operating coil when said armature moves to said closed circuit position, whereupon said armature is held by said magnet, a second operating coil on said field structure, connections for energizing said second coil to neutralize the effect of said permanent magnet and release said armature whereupon said switch opens in accordance with its bias, a third operating coil on said field structure, and connections for energizing said third coil in response to the current in said switch so as to neutralize said magnet and open said switch upon the occurrence of a predetermined current in said switch.

25 5. The combination with a switch provided with a movably mounted circuit controlling member biased to one position, an armature connected to said circuit controlling member, a field structure provided with a portion of permanently magnetizable material forming a magnet for holding said armature in an attracted position, an operating coil on said field structure for moving said armature to said attracted position,

a relay switch biased to the open position, a coil for operating said relay switch to the closed position, a switch member biased to one position to close a circuit for said relay coil and thereby normally maintain said coil energized and said relay switch closed, a connection whereby said relay coil is energized through said relay switch after said relay switch has closed, switching means for said operating coil closed by movement of said switch member to another position, and a switch operated by said armature for opening the circuits of said relay coil and said operating coil.

10 6. The combination with a switch provided with a movably mounted contact biased to its open circuit position, an armature connected to operate said movable contact to its closed circuit position, a field structure provided with a portion of permanently magnetizable material forming a magnet for holding said armature in said closed circuit position, an operating coil on said field structure for moving said armature to said closed circuit position whereupon said operating coil may be deenergized and said armature held in said closed circuit position by said magnet, a second coil on said field structure, and electrical connections for energizing said second coil in accordance with the current in said switch so as to neutralize said magnet and thereby open said switch upon the occurrence of a predetermined current in said switch.

15 7. The combination with a switch provided with a movably mounted circuit controlling member biased to one position, an armature connected to said circuit controlling member, a field structure provided with a portion of permanently magnetized material forming a magnet for holding said armature in an attracted position, a pair of relay switches biased to the open position, a coil for operating said relay switches to their closed positions, a switch member biased to one position to close a circuit for said relay coil and thereby maintain said coil energized and said relay switches closed, electrical connections whereby said relay coil is energized through one of said relay switches after said relay switch is closed, an energizing circuit for said operating coil including the other one of said relay switches and switching means closed by movement of said switch member to another position, and a switch connected in circuit with said relay coil and operated by movement of said armature to said attracted position for opening the circuit of said relay coil.
